UNITED STATES PATENT OFFICE.

HENRY HORAN, OF EAST ORANGE, NEW JERSEY, ASSIGNOR TO THE HARTFORD CARPET COMPANY, OF HARTFORD, CONNECTICUT.

DESIGN FOR A CARPET.

SPECIFICATION forming part of Design No. 11,860, dated July 13, 1880.

Application filed February 12, 1880. Term of patent 3½ years.

To all whom it may concern:

Be it known that I, HENRY HORAN, of East Orange, in the county of Essex and State of New Jersey, have invented a new and original 5 Design for a Carpet, of which the following is a specification.

This invention relates to a new and original design for carpets, oil-cloths, and similar fabrics.

10 It consists in the novel grouping and configuration of figures hereinafter more fully described and claimed.

The accompanying photograph illustrates a face view of a carpet having my new design.

15 The design is composed of the floral groups A B C D E F, arranged on the background of the carpet. The large principal group A consists of a body of leaves and flowers and leafy branches having flowers and rose-buds 20 extending from it in every direction. Group B is composed of a smaller body of leaves and flowers, from which rose-buds and maple and oak leaves extend. Group C is composed of a spray of leaves and buds and of a large open 25 rose. Group D is composed of flowers, buds, and leafy branches extending from it. Group

E is composed of leaves, flowers, and rose-buds placed on the field or background of the carpet between groups B, C, and D. Group F is composed of branches of leaves and buds 30 and flowers twined together. Sprays and branches of the several groups extend over the ground of the carpet, so as to unite the groups with each other into one harmonious design.

35 I claim—

1. The design for a carpet, consisting of the groups A B and uniting branches, substantially as shown.

2. The design for a carpet, consisting of the 40 groups B C D E and uniting branches, substantially as shown.

3. The design for a carpet, consisting of the groups A B F and uniting branches, substantially as shown.

4. The design for a carpet, consisting of the 45 groups A B C D E F and uniting branches, substantially as shown.

HENRY HORAN.
